UNITED STATES PATENT OFFICE

MARVIN L. CHAPPELL, OF LOS ANGELES, CALIFORNIA, ASSIGNOR TO STANDARD OIL COMPANY OF CALIFORNIA, OF SAN FRANCISCO, CALIFORNIA, A CORPORATION OF DELAWARE

PROCESS OF TREATING PETROLEUM OIL TO PRODUCE LOW BOILING POINT OIL

Application filed September 16, 1926. Serial No. 135,845.

This invention relates to a process of treating petroleum oil to produce low boiling point oil such as naphtha or gasoline, and refers also to the production of a novel form 5 of low boiling point oil or gasoline as produced by the process.

There are many petroleum oils which are high in sulphur content and which, when directly subjected to heat and pressure for 10 the purpose of decomposing the same into lower boiling point oils, produce oils which possess a high sulphur content, which sulphur content is extremely difficult to remove from the cracked naphtha.

15 There are also a number of different hydrocarbon oils, which, due either to their high sulphur content or their high content of unsaturated materials, cannot be profitably cracked by a pressure cracking system 20 to produce low boiling point materials. For example, the high boiling point materials derived from the cracking process, such as the steam still bottoms, contain a large percentage of unsaturated constituents, and accord- 25 ingly, if such oils are directly heated under temperature and pressure to decompose the oils into lower boiling point oils, they rapidly carbonize and give a very low yield. This is particularly true of such oils when they 30 have been derived from an asphaltic or California base crude. Also such oils as are obtained in a sulphur dioxide extract of petroleum oils are substantially unsaturated materials and aromatic materials, and give 35 very high losses if the same are directly subjected to heat and pressure in order to decompose the same into low boiling point materials.

40 It is the object of the present invention to provide a process for producing low boiling point oils or naphtha from petroleum oils or hydrocarbons, which is adapted to both substantially reduce the sulphur content of the oils and substantially eliminate the unsat- 45 urated constituents of the oils before they are subjected to a cracking operation under heat and pressure, with the result that many oils, such as high sulphur bearing oils or oils containing a high percentage of unsaturated materials, may be cracked with a materially

higher yield and produce a materially superior product.

In accordance with the present invention, an oil containing a substantial percentage of unsaturated materials or containing a substantial percentage of sulphur or both is first subjected to treatment with a metallic halide, such as aluminum chloride or zinc chloride, iron chloride, etc., under conditions to effect mainly a polymerization of the unsaturated constituents into saturated constituents and to remove the larger portion of the sulphur constituents of the oil. The stock thus treated is then subjected to the requisite temperature and pressure to decompose said oil to form a low boiling point oil or naphtha. The process of the present invention is preferably a continuous process.

The present invention also results in a novel form of low boiling point oil or naphtha 70 which is to be distinguished from the prior oils of this character, in that it combines high nondetonating properties together with a high solubility in sulphuric acid and a low sulphur content. The naphtha of the present invention being produced following both a polymerization reaction in which the constituents of the oil are largely converted to the cyclic compounds and by a temperature and pressure cracking or decomposing reaction in 75 which unsaturated materials are produced therefrom, possesses non-detonating properties superior to that produced either from a straight cracking operation or from a normal aluminum chloride process, and also possesses an unusually low sulphur content.

Various further objects and advantages of the present invention will be apparent from the description of a preferred form or example of a process embodying the invention. For this purpose, reference is made to the accompanying drawings, in which there is illustrated a form of apparatus in which the process of the present invention may be performed.

The drawings represent a diagrammatic view of the apparatus, in which the parts are mainly in vertical section.

Referring to the drawings, the preferred continuous process is performed by passing 100

the fresh oil to be treated from line 2 by means of a pump 6 through a pre-heater 3 to line 4 into an aluminum chloride reaction chamber 5. The process is described referring to 5 aluminum chloride, which is to be regarded as merely an example of a metallic halide as other metallic halides may be employed. The oil to be treated may be any hydrocarbon oil, whether derived from shale, coal or petroleum, 10 but the process is particularly valuable for the treatment of such oil as is either high in sulphur or high in unsaturated constituents. Preferably the oil is heated in the pre-heater 3 to substantially the reaction temperature 15 desired in reaction chamber 5. Said temperature will depend largely upon the character of oil supplied to the system and the percentage of aluminum chloride provided for reacting therewith, also upon whether it 20 is desired to produce a material percentage of naphtha from the aluminum chloride reaction. When it is desired to produce substantially only polymerized stock, the temperature will normally range from 100° F. to 25 450° F., and usually around 300° F. In certain cases it may be desirable to produce a substantial percentage of naphtha from aluminum chloride reaction as well as to polymerize the remainder of the stock, and in this 30 case temperatures as high as 600° F. or higher may be employed. I generally prefer, in operating upon an oil high in sulphur content, to permit at least some conversion of the oil into the low boiling point naphtha in 35 reaction chamber 5, in order to more efficiently remove therefrom the sulphur bearing constituents.

The reaction chamber 5 is preferably a horizontal cylindrical chamber provided with 40 a shaft 7, and mounted within the chamber is a paddle or scraper 8 to provide a means for agitating tarry residue which will collect within the chamber. When it is desired to operate the process continuously, the chamber is preferably provided with a baffle 9 forming at one end of the chamber a separating compartment 10 wherein the oil and tar can settle so the said constituents may be continuously or intermittently withdrawn 45 from the reaction chamber 5 so that said reaction chamber 5 may be continuously operated. The reaction chamber 5 is also indicated as preferably mounted over furnace 11, provided with a burner 12, or other suitable 50 heating means, so that when desired further heat may be supplied to the materials within reaction chamber 5 to maintain the desired reaction temperature, although in certain cases no heat may be supplied to said chamber, and reliance placed solely on the heat of the incoming oil from the pre-heater 3.

The reaction chamber 5 is also indicated as connecting through an inlet 13 having a valve 14 with a charging chamber 15. Said charging chamber 15 is in turn connected

with a line 16 which may lead to a source of anhydrous aluminum chloride. The aluminum chloride may be made liquid by mixing with sufficient oil, as is the usual practice. In the operation of the process, anhydrous aluminum chloride is continuously or intermittently fed from line 16 through charger 15 and inlet 13 into reaction chamber 5. The charger 15 is provided for use where the reaction in chamber 5 is intended to be operated under pressure.

The process of the present invention may be operated either with or without a pressure above atmospheric. Where pressure above atmospheric is employed, the anhydrous aluminum chloride is intermittently fed into the reaction chamber 5 by first closing the valve 14, placing a desired quantity of aluminum chloride in charger 15, then closing valve on line 16 and opening valve 14 to empty the charge into the reaction chamber.

The quantity of aluminum chloride to be employed will also depend upon the character of oil fed into the reaction chamber, the temperature employed in the reaction chamber, and the amount of naphtha, if any, which it is desired to produce within said chamber. Normally this percentage will vary from between .5% and 10% aluminum chloride by weight. In certain cases it is desirable to add in the reaction chamber 5 considerable excess aluminum chloride over that necessary for the desired polymerizing reaction, and limit the reaction mainly to a polymerizing reaction by the employment of low temperatures, in which case the partly spent aluminum chloride residue in reaction chamber 5 may be later employed in other aluminum chloride conversion processes. A small amount of aluminum chloride may be employed in the reaction chamber where high temperatures are desirable, and thereby the reaction can be limited mainly to a polymerizing action.

In any case the aluminum chloride and oil are continuously agitated together within the reaction chamber 5 with the result that an aluminum chloride tar or residue is continuously formed, which settles within the lower portion of compartment 10 and is therefrom withdrawn to the residual line 17 either continuously or intermittently. Where the reaction in chamber 5 is controlled solely to polymerize the oil stock, said polymerized oil stock is continuously withdrawn from the upper portion of compartment 10 through line 18 by pump 19, and then continuously conducted into the pressure cracking portion of the apparatus. The line 18 is preferably provided with a trap 20, in which may be separated any aluminum chloride residuum which might be entrained in the polymerized oil passing through said line. Normally the operation will result in the production of at

least some naphtha, in which case said naphtha is preferably continuously vaporized from the oil within reaction chamber 5, and passed through the vapor line 21 into a dephlegmator 22, wherein the heavy polymerized stock may be separated from the produced naphtha, and wherein any entrained aluminum chloride may also be separate.

10 The dephlegmator 22 is indicated as provided at its upper portion with a planer 23 through which a cooling medium may be passed from line 24 and 25 to effect the desired refluxing and control the temperature of the discharged vapors. The discharged naphtha vapors are preferably passed through line 26 and condenser 27 into a naphtha receiver 28. The naphtha receiver 28 is indicated as provided with a valved gas 15 outlet 29 and a pressure gauge 30 by which the pressure applied to the system may be controlled.

At the bottom of the dephlegmator there is provided a settling space for polymerized oil and aluminum chloride condensed from the vapors within said dephlegmator. Any aluminum chloride settled may be continuously passed through a return line 31 and back again into the reaction chamber 5 together with said polymerized oil, but preferably the polymerized oil is withdrawn through line 32 and passed together with other polymerized oil from line 18 into the pressure cracking apparatus of the process. 30 In certain cases it may be desirable to vaporize all of the polymerized oil and later collect the same in the dephlegmator 22, and pass all the polymerized oil therefrom to the pressure cracking apparatus, in place of withdrawing any of said oil through the line 18.

The reaction chamber 5 may be operated at atmospheric pressure or below atmospheric pressure, but I generally prefer to employ a pressure above atmospheric, such as from 15 to 50 pounds per square inch or greater. Said pressure permits a higher temperature to be employed within the reaction chamber 5, and consequently more efficient utilization of aluminum chloride, and also facilitates the clean separation of the produced naphtha from polymerized oil, which is desired to be charged to the pressure cracking portion of the apparatus.

The oil withdrawn by pump 19 is substantially free of unsaturated constituents and contains a large percentage of cyclic compounds and an extremely low percentage of sulphur, and constitutes an exceptionally desirable charging stock for a pressure cracking plant. Said oil is then subjected to the requisite temperature of cracking to cause said oil to decompose and form low boiling point oil or naphtha. This portion of the process may be performed in a great variety 60 of ways.

I have indicated a preferred process and apparatus for conducting this pressure decomposition. In the said preferred process and apparatus the oil from pump 19 is passed through a heating coil 32a within a furnace 33, in which the temperature of the oil is preferably raised to a temperature between 750° F. and 900° F. From the heating coil 32a the oil is passed through a line 34 into a reaction chamber 35. Within the reaction chamber 35 the oil is held under pressure suitable to maintain the same in the liquid state until the cracking or decomposition reaction is complete. The pressure generally ranges from 80 pounds to 300 pounds per square inch, although higher pressures may be employed. The produced naphtha is continuously vaporized from the reaction chamber 35 and passed through vapor line 36 to a dephlegmator 37. The oil within the reaction chamber 35 may be reduced to naphtha and a tarry residue which may be continuously withdrawn from the line 38, or the oil may be reduced to naphtha and coke. In case it is intended to form coke within reaction chamber 35, the chamber is preferably provided with suitable means, such as a wire cable 39, by which said coke may be withdrawn therefrom.

The naphtha vapors passing into dephlegmator 37 are therein separated from any non-decomposed oil, which is preferably returned through reflex line 40 back to the stream of fresh polymerized oil being passed into the heating coil 32a. The dephlegmator 37 is indicated as preferably provided with a planer 41 as a suitable temperature control means.

The cracked naphtha is passed from dephlegmator 37 through line 42 and condensed in condenser 43 and discharged into the naphtha receiver 44. Said naphtha receiver is indicated as provided with a gas outlet line 45 having a valve 46 with a gauge 47. By said means the pressure throughout the pressure decomposition apparatus may be controlled.

The pressure naphtha produced in accordance with the process of the present invention possesses less sulphur compounds than pressure naphtha produced in other pressure crackling processes, and moreover is composed of ingredients derived through both a polymerization and pressure decomposition reaction, so that the naphtha is of different character than that ordinarily derived from petroleum oil, either by straight distillation aluminum chloride treatment or pressure distillation, and is superior in non-detonating properties to normal naphtha.

The important feature or advantage of the process of the present invention is the ability to successfully process oils containing a high percentage of unsaturated materials. For example, at the present time the oils extracted

from petroleum oil by sulphur dioxide in different purification processes have at present no value except as fuel oil. The present invention permits said oils to be readily polymerized and then cracked into a high grade naphtha.

While the particular process herein described is well adapted to carry out the objects of the present invention, various modifications and changes may be made without departing from the spirit of the invention. The invention includes all such modifications and changes as come within the scope of the appended claims.

15 I claim:—

1. A process of producing low boiling point oil or naphtha from oil recovered from a sulphur dioxide extract of a hydrocarbon oil, which comprises heating and contacting 20 such oil with an anhydrous aluminum chloride under conditions to polymerize a part of said oil, separating the polymerized oil from the aluminum chloride tar and then subjecting the polymerized oil to the requisite temperature and pressure to decompose the oil or crack it to form low boiling point oil or naphtha.

2. A process of converting hydrocarbon oil into naphtha which comprises heating and subjecting said oil to reaction with anhydrous metallic halide, to polymerize a part of said oil and to decompose a part of said oil into naphtha, simultaneously vaporizing from the material undergoing treatment a mixture of polymerized oil and naphtha, passing said mixture into a reflux zone wherein said naphtha is separated from said polymerized oil and said polymerized oil is condensed, passing said polymerized oil containing no metallic halides from said reflux zone through a pressure cracking chamber and therein subjecting said oil to the requisite temperature and pressure, to thermally decompose or crack said oil 45 to form additional naphtha.

3. A process of producing low boiling point material from a hydrocarbon oil which comprises continuously heating the oil and passing the same into a reaction zone, therein 50 continuously subjecting said oil to reaction with an anhydrous metallic halide, to polymerize a part of said oil and to decompose a part of said oil to form naphtha, continuously vaporizing said naphtha together with a part of said polymerized oil, and passing the same through a reflux zone, continuously separating from said reflux zone said naphtha from said polymerized oil and continuously 55 passing said polymerized oil containing no metallic halides from said reflux zone together with polymerized oil from said reaction zone into a cracking zone, and therein continuously subjecting said oil to the requisite temperature and pressure to thermal- 60 65

ly decompose or crack said oil and form low boiling point oil.

Singed at San Francisco this 28th day of August, 1926.
